UNITED STATES PATENT OFFICE.

MILLARD F. CARR, OF WHITESTOWN, INDIANA.

SACK-TIE.

SPECIFICATION forming part of Letters Patent No. 367,785, dated August 9, 1887.

Application filed January 22, 1887. Serial No. 225,238. (No model.)

To all whom it may concern:

Be it known that I, MILLARD F. CARR, a citizen of the United States, residing at Whiteside, in the county of Boone and State of Indiana, have invented a new and useful Improvement in Sack-Ties, of which the following is a specification.

My invention relates to an improved device for closing and securing the mouth of a grain-sack.

The object of my improvement is to provide a light metallic tying device which may be secured to a sack, so as to be always in readiness for use, and which may be quickly operated for securing or releasing the mouth of the sack, as hereinafter fully described.

The accompanying drawings illustrate my invention.

Figure 1 represents a sack with my tie attached and unfastened. Fig. 2 is a perspective view of the tie when open. Fig. 3 is a perspective view of the tie when closed but not secured. Fig. 4 is a plan view showing the tie secured.

The body of my tie consists of a piece of wire bent to form a pair of arms, *b* and *c*, adapted to embrace the closed mouth of the sack, an eye, *d*, hooks *e* and *f*, and an eye, *h*.

B is a link having an eye at each end, one of which eyes engages the eye *h*, and to the other is secured the bent lever *l*. Arms *b* and *c* are of sufficient length to embrace the closed mouth of the sack on three sides, and link *B*,

with the shorter arm of lever *l*, are of sufficient length to connect the hooks *e* and *f* and 35 complete the encirclement of the mouth of the sack.

The tie is secured permanently to the sack by means of a rivet or a few stitches passed through eye *d* and the sack; or said eye may 40 be omitted and the stitches passed over the arms.

The operation of my device is as follows: The mouth of the sack having been drawn together within the arms *b* and *c*, the bight of 45 lever *l* is engaged with hook *e*, as shown in Fig. 3. The long arm of lever *l* is now drawn toward the sack until the free end of the lever drops into hook *f*, thus drawing arms *b* and *c* toward each other and at the same time throwing link *B* inward. The mouth of the sack is thus, with great ease to the operator, closely compressed and strongly secured.

I claim as my invention—

In a sack-tie, the single piece of wire bent 55 to form the arms *b* and *c*, adapted to embrace the closed mouth of a sack on three sides, arm *c* terminating in the hook *e*, and arm *b* terminating in the eye *h* and hook *f*, the link *B*, and the bent lever *l*, all combined and arranged 60 to co-operate to secure the mouth of a sack in the manner specified.

MILLARD F. CARR.
